(57) **CLAIM**

The ornamental design for a fold-able container, as shown and described.

DESCRIPTION

FIG. 1 is a front elevational view of my fold-able container, note the strap is connected to the strap rings. A logo is shown in phantom.

FIG. 2 is a rear elevational view of my fold-able container, with strap in place.

FIG. 3 is a right side elevational view of my fold-able container. Note the strap is attached to the D ring.

FIG. 4 is a left side elevational view of my fold-able container. Note that the strap is detached, and the flap covers the D ring.

FIG. 5 is a top plan view of my fold-able container. Note that the roundly configured top obscures the side planar panels of the fold-able structure. The strap is shown in place; and, FIG. 6 is a bottom plan view of my fold-able container. The strap attachments are visible, and the rounded top is visible, along with the planar sides and the flaps.
